UNITED STATES PATENT OFFICE.

CHRIST F. DOTTS, OF MILLVALE, PENNSYLVANIA, ASSIGNOR OF ONE-THIRD TO DAVID MOORE, OF PITTSBURGH, PENNSYLVANIA.

WIRE-LINE CLAMP.

1,403,152.

Specification of Letters Patent. Patented Jan. 10, 1922.

Application filed May 7, 1920, Serial No. 379,619. Renewed March 14, 1921. Serial No. 452,230.

To all whom it may concern:

Be it known that I, CHRIST F. DOTTS, a citizen of the United States, residing at Millvale, in the county of Allegheny and State of Pennsylvania, have invented new and useful Improvements in Wire-Line Clamps, of which the following is a specification.

This invention relates to clamps, and more particularly to wire line clamps specially adapted for use in oil well drilling and similar operations.

One of the main objects of the invention is to provide a clamp of simple construction which is composed of a minimum of parts and may be readily assembled. A further object is to provide a clamp composed of two similar members thus reducing the cost of production. Another object is to provide simple and efficient means for connecting the gripping jaws or elements of the clamp and for positively preventing relative vertical movement of these jaws when the clamp is applied. Another object is to provide a clamp the jaws of which are so related and connected as to exert a maximum gripping effect up the line, simple and efficient means being provided for forcing the jaws into gripping engagement with the line. Further objects will appear from the detailed description.

In the drawings:—

Figure 1 is a top view of a clamp constructed in accordance with my invention.

Figure 2 is a front view.

Figure 3 is a back view.

Figure 4 is a section taken substantially on line 4—4 of Figure 1.

Figure 5 is a top plan view of one of the clamp members.

Figure 6 is a similar view of the other clamp member.

In constructing the clamp I provide two jaws 1 and 2 of segmental cross section, each of these jaws being provided in its inner face with a vertically extending groove 3 of arcuate cross section, these grooves being adapted to receive sections 4 of a suitable liner. Each section of the liner is provided with an outwardly projecting boss 5 which fits into a corresponding recess in the jaw, these bosses being bored and threaded to receive screws 6 inserted through the jaws by means of which the sections of the liner are detachably secured in position. The bosses 5 serve to support the load thus re-

lieving the usual collar 7 at the upper end of the liner of strain.

Jaw 1 is provided adjacent to its lower end with an integral arm 8 of substantially circular shape, jaw 2 being provided adjacent to its upper end with a similar arm 9 which is directed oppositely to arm 8. When the clamp is assembled, arm 8 extends about jaw 2 and arm 9 extends about the upper portion of jaw 1, these arms serving to connect the two jaws as illustrated for movement toward and away from each other about the common axis of the arms, it being understood that the jaws fit snugly within the connecting arms. Each jaw is provided with an integral shoulder 10, these shoulders being in contact with the arms and serving to positively prevent relative vertical movement of the jaws. Each jaw is further provided at its upper end with an integral arm or hook 11, these hooks receiving the usual suspending links 12 by means of which the clamp is suspended from the temper bar.

Jaw 1 is provided with an outwardly projecting lever arm 13, jaw 2 being provided with a similar arm 14. A substantially U-shaped clevis 15 is pivoted by a pin 16 to ears 17 projecting from the outer face of arm 13 adjacent to the outer end thereof.

A T-screw 18 is threaded through the bight of the clevis, and has its inner end reduced to provide a pressure element 19 the inner end of which is rounded to fit into a corresponding recess in a boss 20 formed on the outer face of arm 14. Member 19 passes through a block 21 slidable between the arms of the clevis, the ends of this block being slotted and fitting snugly about the clevis arms. A cotter pin 22 is inserted through element 19 adjacent to the inner face of block 21. The block is thus connected to screw 18 so as to travel longitudinally of the clevis in accordance with operation of the screw. The block 21 is positioned closely adjacent to the inner end of element 19, and this block serves to effectually brace this element so as to eliminate breakage thereof while also serving to guide element 19 into engagement with boss 20.

As will be noted more clearly from Figure 1, the inner ends of jaws 1 and 2 form radii of the circle enclosed by arms 8 and 9, and the grooves 3 of the jaws are positioned in

advance of the axis about which the jaws operate, the point of intersection of the planes of the inner ends of the jaws being substantially co-incident with this axis. 5 When the clamp is in gripping engagement with a cable the line of fulcrum of the jaws on the arms 8 and 9, indicated by line $x-x$ in Figure 1, will pass immediately in back of the liner thus insuring a maximum gripping effected for a given pressure exerted upon the lever arms 13 and 14. By means of the screw 18 great pressure can be exerted upon these arms to insure effective gripping of the line and effectually eliminate all possibility of slippage thereof. As the jaws 1 and 2 are connected directly to the temper bar and are effectually secured against relative vertical movement, I insure that the drilling apparatus will be 15 properly suspended, and excess strain upon any part of the clamp due to one jaw being subjected to greater load than the other is eliminated.

What I claim is:—

- 25 1. In a wire line clamp, two clamping jaws, and means carried by and integral with said jaws for connecting the same so as to be movable toward and away from each other.
- 30 2. In a wire line clamp, two clamping jaws of substantially segmental cross section, an arm carried by each jaw and encircling the other jaw, said arms connecting the jaws for movement toward and 35 away from each other, and members carried by the jaws and in contact with the

arms acting to prevent relative vertical movement of said jaws.

3. In a wire line clamp, two clamping jaws of segmental shape, each of said jaws 40 being provided with an outwardly projecting shoulder, and an arcuate arm carried by each of said jaws and encircling the other jaw, said arms fitting above and below said shoulders and connecting the jaws 45 for movement toward and away from each other, the arms and the shoulders cooperating to positively prevent relative vertical movement of the jaws.

4. In a clamp the combination of two 50 blocks constituting each a cylindrical segment and provided each with an extension adapted to encircle the cylindrical surface of the other block, whereby the two blocks are assembled rotatably upon a common axis, and means for exerting upon said blocks in the direction of relative rotation a clamping stress.

5. In a clamp the combination of two blocks constituting each a cylindrical segment 60 and provided each with an extension adapted to encircle the cylindrical surface of the other block, whereby the two blocks are assembled rotatably upon a common axis, the said blocks being further provided 65 each with a lever arm and each with a work-engaging recess spaced at an interval from the axis of turning.

In testimony whereof I affix my signature.

CHRIST F. DOTT.
